DESIGN FOR A TIRE

Robert S. Lee, Eau Claire, Wis., assignor to National Co-Operatives, Inc., Chicago, Ill., a corporation of Indiana

Application December 13, 1939, Serial No. 88,865

Term of patent 3½ years

To all whom it may concern:

Be it known that I, Robert S. Lee, a citizen of the United States, residing at Eau Claire, in the county of Eau Claire and State of Wisconsin, have invented a new, original, and ornamental Design for a Tire, of which the following is a specification, reference being had to the accompanying drawing, forming a part thereof and in which

Fig. 1 is a development of the tread portion of a tire showing my new design;

Fig. 2, a cross section of the tire taken substantially on line 2—2 of Fig. 3; and

Fig. 3, a side view of a portion of the tire.

I claim:

The ornamental design for a tire, as shown.

ROBERT S. LEE.
